Norman B. McCreary, Little Rock, Ark.

Application June 21, 1943, Serial No. 491,672

3 Claims. (Cl. 211—73)

The invention relates to improvements in display stands for displaying merchandise for sale, and has for its primary object the provision of a simple arrangement of the character indicated which may be of a single sheet of foldable material and is of simple and economical construction and highly efficient in use. Other objects will appear hereinafter.

The invention consists of the combinations and arrangements of parts hereinafter described and claimed.

The invention will be best understood by reference to the accompanying drawings forming a part of this specification and in which—

Fig. 1 is a plan view of a blank cut and scored for the formation of a display stand embodying the invention; Fig. 2, a partial perspective view of one end of

the arrangement shown in an initial stage of assembly; Fig. 3, a similar view showing one end of the arrangement in a later stage of assembly;

Fig. 4, an enlarged sectional view taken substantially on line 4—4 of Fig. 3; Fig. 5, a view similar to Figs. 2 and 3 but showing the arrangement in a later stage of assembly; and Fig. 6, a perspective view of the complete stand assembled in condition for use.

The embodiment of the invention illustrated in the drawings comprises a blank formed from a single sheet of foldable material, cut and scored to form a container bottom wall 10 having triangular end flaps 11, foldable downwardly to form supports for said bottom wall and arranged to position said bottom wall at a suitable upwardly and rearwardly extending angle to the horizontal, as best shown in Fig. 2. A lower front wall 12 is arranged at the lower front edge of, and foldable upwardly at substantial right angles to, said bottom wall 10, and a lower front panel 13 is formed at the top edge of, and foldable downwardly with respect to said front wall into substantially vertical position, also as best shown in Fig. 2. The front wall 12 carries at its ends substantially triangular enclosing flaps or walls 14, foldable against and inwardly around the rear edges of said supporting flaps 11 and of a size and shape to cover said supporting flaps 11, and also constitute end walls for said container, as best shown in Fig. 3. Slits 11' are formed in the supporting flaps 11 in positions to receive the points 14' of the flaps 14 when so folded, thereby locking the parts in the positions indicated in Fig. 3. As shown in Fig. 1, each flap 14' is provided with a

notch 11'' which interlocks with the corresponding end of the slot 11', thereby further securing the parts in place. A rear wall 15 is formed at the upper rear edge of, and foldable upwardly at substantially right angles to said bottom wall 10 and having at its ends covering flaps 16, of a size and shape to cover the exposed portions of said enclosing flaps 14, securing flaps 15 being formed at their free ends so as to be insertable between said front wall 12 and panel 13, as best indicated in Fig. 3. Binding strips 13' are arranged at the ends of the panel 13 and are of a length to traverse the lower edges of the covering flaps 16 and provided at their ends with lock flaps 13'' insertable in slits 14'' provided at the folds of the enclosing flaps 14, as best indicated in Fig. 5.

By this arrangement a merchandise display container is provided which is formed from a single sheet of material without the use of glue or other fastenings and will contain and support articles of merchandise displayed at a suitable angle and in a manner well adapted to facilitate the sales thereof.

In order to further reinforce the construction thus made, a top panel 18 is provided at the upper edge of, and foldable upwardly at an angle to, said rear wall 15 and having triangular position walls 19 at its ends foldable at right angles thereto and carrying holding flaps 20 foldable inwardly behind said top panel 18, as best indicated in Figs. 3 and 5. A back member 21 is provided at the top edge of the panel 18 and is foldable downwardly into substantially vertical position, carrying at its ends inwardly foldable holding strips 22, forwardly foldable side walls 23 and pointed holding flaps 24. The forwardly foldable side walls 23 when folded forwardly against the covering flaps 16 place the holding flaps 24 in positions to be folded downwardly over the insides of flaps 16, with the holding flaps 24 inserted between the ends of the bottom wall 10 and the adjacent flaps and walls, as best indicated in Figs. 5 and 6. A forwardly foldable bottom support 25 is formed at the lower edge of said back member 21 and has at its forward end an upwardly foldable holding flap 26 which carries inwardly foldable side strips 27, both of which are insertable behind said lower panel 13, as best indicated in Figs. 3 and 5. The bottom support 25 is also provided with upwardly foldable outer end walls 28 of a size and shape to cover said forwardly foldable side walls 23 and carrying tuck-in flaps 29 and 30. When the walls 28 are folded upwardly against the outer sides of the side walls 23, the tuck-in flap 29 is carried

to a position for insertion behind the panel 18 and the flap 30 to a position for folding over the upper edges of the container walls, and downwardly to be inserted at the ends of the bottom of said container, as best indicated in Fig. 6. By this arrangement the display container will be fully reinforced and stiffened so as to render it capable of carrying relatively heavy articles for display, as will be readily understood.

If desired, the front faces of panels 13 and 18 and the outer faces of the side walls 28 may be provided with suitable advertising matter, or suitable advertising panels may be readily attached to the stand thus provided by having their ends inserted in the various folds thereof.

In this way a display rack is provided which is cut from a single piece of material folded upon, and interlocking with itself, to form a complete elevated merchandise display stand or rack, with the merchandise elevated and displayed at a proper angle; the complete construction being cut from a single piece of flat material may be shipped in flat form, thus conserving shipping space and readily extended into operative condition by simply making a few folds as outlined above; the advertising spaces thus provided are all on one side of the material, thus greatly facilitating the printing and finishing thereof; over 99 per cent of the material of the blank is utilized for supporting and stiffening purposes, thus involving comparatively little waste of material; and the entire stand is constructed in such a manner as to avoid the necessity for the use of glue or other fastening means.

The specific form and arrangement of parts disclosed is a simple and effective one for the purpose.

While I have illustrated and described the preferred form of construction for carrying the invention into effect, this is capable of variation and modification without departing from the spirit of the invention. I therefore do not wish to be limited to the precise details disclosed, but desire to avail myself of such variations and modifications as fall within the scope of the appended claims.

I claim:

1. A display stand formed from a single blank of foldable material cut and scored to form a container bottom wall having triangular flaps foldable downwardly to form supports for said bottom wall at an upwardly and rearwardly extending angle to the horizontal; a lower front wall at the lower front edge of, and foldable upwardly at substantially right angles to said bot-

tom wall and a lower front panel at the top edge of, and foldable downwardly with respect to said front wall into substantially vertical position, said front wall carrying at its ends substantially triangular enclosing flaps foldable against, and inwardly around, the rear edges of said supporting flaps, and of a size and shape to cover said supporting flaps and also constitute end walls for said container, there being slits in said supporting flaps into which the points of said enclosing flaps are inserted; a rear wall at the upper rear edge of, and foldable upwardly at substantially right angles to said bottom wall and having at its ends covering flaps of a size and shape to cover the exposed portions of said enclosing flaps, there being at their forward free ends securing flaps insertable between said front wall and panel, said panel carrying at its ends binding strips of a length to traverse the lower edges of said covering flaps and having at their ends locking flaps, there being slits at the folds in said enclosing flaps to receive said locking flaps.

2. The construction specified in claim 1 in which an extension is provided at the upper edge of said rear wall foldable around the rear bottom and sides of said container and its supports to reinforce the same.

3. The construction specified in claim 1 in which a top panel is provided at the upper edge of, and foldable upwardly at an angle to, said rear wall and having triangular positioning walls at its ends foldable at right angles thereto and carrying holding flaps foldable inwardly behind said top panel; a back member at the top edge of said panel foldable downwardly into substantially vertical position and carrying at its ends inwardly foldable holding strips, forwardly foldable side walls and pointed holding flaps foldable downwardly over the inside of said covering flap with their points inserted between the ends of said bottom wall and the adjacent flaps and walls; a forwardly foldable bottom support at the lower edge of said back member having an upwardly foldable holding flap at its forward end and carrying inwardly foldable side strips, both insertable behind said lower front panel, said bottom support also having upwardly foldable outer end walls of a size and shape to cover said forwardly foldable side walls and carrying tuck-in flaps foldable over the upper edges of the complete outer side walls of the container and inserted respectively behind said top panel and at the ends of said container bottom wall.

55 NORMAN B. McCREARY.
